INVENTOR

Henry B. Haigh
BY James C. Chapman
His ATTORNEY

UNITED STATES PATENT OFFICE.

HENRY B. HAIGH, OF NEW YORK, N. Y.

METAL BARREL.

SPECIFICATION forming part of Letters Patent No. 665,003, dated January 1, 1901.

Application filed April 18, 1898. Serial No. 677,908. (No model.)

To all whom it may concern:

Be it known that I, HENRY B. HAIGH, a citizen of the United States of America, and a resident of New York, (Brooklyn,) county of 5 Kings, State of New York, have invented certain new and useful Improvements in Metal Barrels, of which the following is a specification.

My invention relates to barrels of that class 10 or type designed to carry fluids or other substances which necessitate a fluid or liquid tight receptacle; and to this end my invention consists of a barrel formed of two or more metallic sections united circumferentially by a ring or coupling-piece of suitable 15 form, the whole being so united and constructed in such a manner that it shall be light in weight, easy and simple of manufacture, yet strong and durable.

The object of my invention is to simplify 20 and reduce the cost of construction of barrels and at the same time to increase their strength, durability, and imperviousness.

My invention further consists of certain 25 novel details of construction, as will herein-after be more fully set forth.

I will now proceed to describe a barrel embodying my invention, with reference to the accompanying drawings, and will then point 30 the novel features in claims.

With reference to the drawings, Figure 1 represents an exterior side elevation of a barrel embodying my invention. Fig. 2 represents a central longitudinal section of the 35 same. Figs. 3, 4, and 5 represent enlarged sections of a portion of the same representing certain steps in the manufacture of the same. Figs. 6 and 7 represent similar sections, but illustrating a slight modification thereof.

Similar reference characters designate corresponding parts throughout the several views.

1 and 2 represent the upper and lower portions of a barrel made in two sections and 45 represented as a whole in said figures. These portions may conveniently be made by a process of cupping disks of metal to the required shape and size in a manner well known and will hence each consist of a single piece of 50 metal without seams.

3 designates an annular ring of ductile metal, such as wrought-iron or steel, forming

a union for the two sheet-metal portions 1 and 2. The said ring has two circumferential grooves 4 and 5 around the same and two flanges 6 and 7 adjacent to said grooves. Said ring is formed with greater thickness through its central portion 8 between the flanges than at any other portion.

The shape of the annular ring is clearly 60 shown in Fig. 3—that is to say, the shape of the same during the manufacture of the barrel and at the time of the assemblage and prior to the connection or union of the parts. During the said manufacture, the parts being 65 assembled as shown in Fig. 3, the edges of the cupped portions will overhang the grooves 4 and 5. The sheet-metal edges 1 and 2 will now be forced down into the grooves and the flanges turned over, substantially as shown in Fig. 70 4. This may be done in any desired manner, as by causing rollers to rotate around the outside of the parts. A finishing-roller of the correct shape adjusted with considerable pressure will bring the parts to the condition 75 shown in enlarged detail in Fig. 5 or on a smaller scale, but showing the entire barrel in Figs. 1 and 2.

In Figs. 6 and 7 the ring is shown as having the grooves 4 and 5 stepped. The sheet-metal portion will be correspondingly shaped, 80 as the edges are to be forced down into the grooves, and the flanges will also assume the same form, a section through the same when completed appearing as in Fig. 7.

A barrel constructed according to my invention will be light in weight, inexpensive in manufacture, and exceedingly strong and durable. It will also be perfectly fluid or liquid tight. The barrel will of course be provided 90 with the usual bung and vent for purposes of filling and emptying the same. It is obvious that the barrel may by thus uniting the sections be made in several sections—as, for instance, by inserting annular sections with 95 open ends between the cup-shaped portions.

What I claim is—

1. A barrel or similar vessel formed of sheet-metal sections divided on transverse planes, a hoop adapted to connect said sections having a plurality of external grooves and a flange between said grooves, said flange and the edges of the sheet-metal sections being forced into said grooves forming shoulders

upon the sheet metal which engage with shoulders upon the body portion of the hoop whereby the strain is taken by the body portion of said hoop; substantially as described.

5. 2. A barrel or similar vessel having sheet-metal sides and divided into two parts on a transverse plane, a hoop adapted to fit within said parts having two external grooves and two flanges between said grooves, said flanges 10 and the edges of the sheets forming the side walls of the parts of the vessel being flanged over each into its respective groove with the flange outermost to secure the parts together.

3. A hollow cylindrical vessel composed of 15 sheet metal and divided into two parts on a transverse plane, and a connecting ring or hoop adapted to fit within said parts and having two grooves in its outer periphery adapted to receive the edges of the sheets forming the 20 vessel ends, the outer edges of said grooves or the edges next the adjacent edges of the

hoop being substantially vertical to its periphery, the hoop also having two flanges adjacent the inner or central edges of the grooves and adapted to be forced each into its respective 25 groove to hold the edges of the sheets in place therein.

4. A connecting-hoop for transversely-separated sections of metal barrels and similar vessels adapted to fit within the ends of adjacent sections and having two peripheral grooves adapted to receive the flanged edges of 30 said sections, and also having two flanges between said grooves adapted to be bent oppositely into said grooves to bind the edges of 35 the sections in place therein.

Signed by me at the city of New York, N.Y., this 2d day of March, 1898.

HENRY B. HAIGH.
